REFRIGERATION DEVICE

William H. D. Brouse, Toronto, Ontario,
CanadaApplication October 16, 1933, Serial No. 693,752
In Canada August 29, 1933

7 Claims. (Cl. 62—4)

The principal objects of this invention are to provide an automatically defrosting refrigerating unit of greatly increased efficiency, reducing in a marked degree the consumption of electric current, and which will also maintain a greater stability of temperature within the chamber cooled by the refrigerating unit than where defrosting is manually exercised.

A further object is to provide an equipment which will automatically defrost the refrigerating unit without raising above a freezing temperature the coils in the section used for freezing materials.

The principal feature of this invention resides in the provision of a refrigerating unit exposed to the atmosphere of the cooling chamber of a refrigerator, in conjunction with sharp freezing coils separated therefrom and insulated or isolated from the cooling chamber atmosphere and in the provision of control means whereby the refrigerant is directed in separate quantities to the freezing coils and refrigerating unit respectively, said freezing coils having an outlet end connected with the refrigerating unit for the release of the evaporated or partially evaporated refrigerant therefrom into the said refrigerating unit.

A further and important feature consists in the novel construction of the means for controlling the supply valve whereby the float control is flexibly mounted to insure the maximum operation of the float within a restricted chamber.

In the accompanying drawing, Figure 1 is a skeleton illustration of the refrigerating system.

Figure 2 is an enlarged elevational part-sectional detail of the expansion chamber with its automatically controlled valve and the connected cooling coils.

Figure 3 is an end elevational view of the portion of the unit illustrated in Figure 2.

In numerous forms of refrigerating devices, the evaporator coils for cooling the refrigerator chamber, are utilized for producing a freezing temperature in a receptacle compartment or compartments separate from but arranged in the refrigerator chamber, and when it is desired to defrost these coils the temperature of the evaporator is raised to such a degree that the freezing quality is destroyed for a sufficient length of time to melt any material in the freezing receptacles in the compartments. This condition is very undesirable and though defrosting operations have in some instances been made semi-automatic, nevertheless the efficiency of the unit as a refrigerating device is detrimentally affected.

The present invention has been devised to over-

come these difficulties with the equipment herein shown and described.

The compressor unit 1 discharges through the pipe 2 to the condenser coils 3 which are arranged outside of the refrigerator and the condensed refrigerant is delivered to the reservoir 4.

A pipe 5 leads from the bottom of the reservoir 4 to the valve casing 6 of the control tank or evaporator 7 which is arranged within the refrigerator. Within the casing 6 is an orifice 8 which is controlled by a needle valve 9 pivotally mounted upon the shank end 10 of a fork 11 arranged within the cylinder 7.

The shank of the fork 11 is mounted on a pivot 12 extending transversely of a lug 13 projecting inwardly from the member 6 and said valve is adapted to be reciprocated by the action of the fork to control the escape of the condensed refrigerating fluid from the orifice 8.

A cylindrical float 14 which is supported by the liquid refrigerant within the tank or evaporator 7 is pivotally mounted midway of its length between the outer ends of the fork 11. This pivotal arrangement of the float 14 on the pivotal fork which operates the control valve allows of the maximum latitude of movement within the minimum diameter of control tank.

The end 15 of the valve is reduced to provide a communicating passage 16 with an opening 17 leading laterally from the valve casing 6 outside of the cylinder 7.

A pipe 18 is secured in the opening 17 and communicates with the freezing evaporator coils 19 which are arranged within the refrigerator but enclosed within a casing 18' which forms a partial insulation. A pipe 20 leads from said freezing coils 19 to an opening in the side wall of the cylinder 7, preferably adjacent to the end opposite to the valve end.

A curved tube 21 arranged within the cylinder 7 is secured at its outer end in a fitting 22 to which the return pipe 23 to the compressor unit is connected. The tube 21 curves upwardly inside of the cylinder to a point close to its upper inner cylindrical periphery. This tube is provided with a perforation 24 at a point lower than its intake end so that any lubricating oil carried to the cylinder will be picked up gradually through this hole leaving the upper open end 50 of the tube above the liquid level for the outlet of evaporated refrigerant.

The evaporator tank 7 is provided with a plurality of holes 25 arranged preferably slightly offset from its vertical diameter, and sealed in these

holes are open refrigerating loops 26 carrying the sheet metal heat-exchanging vanes 27.

When the condition of the refrigerating fluid within the tank 7 and its associated tubular loops 5 is such as to permit a predetermined rise of temperature within the chamber which is cooled thereby, the compressor is started and draws off vaporized refrigerant through the pipe 23 which effects the lowering of the liquid level as evaporation continues and as the level of the refrigerant lowers in the tank 7, the float arm 11 will be lowered to operate the valve 15 to open the orifice 8 admitting a further quantity of the condensed refrigerant, so that a substantially uniform level 10 is maintained in the tank 7 and as evaporation takes place the temperature of the tank and loops 15 is lowered to thereby cool the surrounding air.

It will of course be understood that the valve 15 will only open a very small degree at any time 20 and that the sudden release of the fluid refrigerant from the high to low pressure through such small opening will result in an expansive effect on the fluid instantly lowering its temperature and serving in a degree to vaporize the 25 refrigerant which vaporizing continues within the coils 19.

The main flow of the condensed refrigerant is conducted from the condenser 3 and reservoir 4 through the pipe 5 and is directed by the valve 9 30 into the pipe 18 and flows through the freezing evaporator coils 19, which are arranged in an insulated chamber separate from the principal cooling section. Thus the refrigerant filling the coils 19 is forcibly evaporated therein in whole 35 or in part due to the suction pressure existing in pipe 20, so that the temperature of the coils is lowered and the vaporized refrigerant or portions of the refrigerant that may not have been evaporated is drawn into the tank 7, and since the coils 40 19 are enclosed within the refrigerator cabinet and partly insulated therefrom a lower temperature will be built up about the vicinity of the coils 19 than will obtain within the main body of the cabinet. The valve 9 is a loose fit in its sliding 45 orifice and a certain amount of the refrigerant escapes directly into the cylinder 7 around the valve.

The cylinder 7 and its loops and heat conducting elements may be made of any desired capacity 50 to maintain a proper temperature in the cooling chamber of the refrigerator in which it is installed in accordance with the design and various dimensions of the equipment. With the arrangement described there will be no appreciable 55 interchange of heat from the refrigerator chamber to the freezing element, either directly or through the cooling element. Therefore the cooling element 26 can be raised in temperature above the melting point of ice to effect the defrosting thereof during the idle part of the cycle, 60 when the compressor is not operating, without materially affecting the temperature of the freezing element.

A suitable thermostatic control device 28 which 65 may be of any conventional form and need not be illustrated in detail herein is arranged adjacent to the casing of the chamber housing the freezing coils and controls the operation of the compressor unit 1. This is connected directly to the casing of the freezing element by a copper 70 strip 28' or equivalent element influentially connected with control device 28 so that it is subject to a temperature between that of the freezing element and the surrounding atmosphere in the cabinet. The thermostat may be so adjusted

that with normal cabinet temperatures, the temperature of the freezing element does not rise above freezing at any time, though the refrigerating chamber may rise to a defrosting temperature during idle periods.

It will be seen that as the main volume of the refrigerant is conducted through the freezing coils 19 where evaporation takes place in whole or in part independent of the evaporation taking place in the loops 26, the defrosting temperature 10 of the cylinder 7 and the refrigerating loops connected therewith will have practically no effect on the cooling element in casing 19'. Consequently water or other substances frozen in the freezing section will not be melted and will not 15 therefore have to be refrozen.

The arrangement of the unit is extremely simple but accomplishes a very desirable result.

What I claim as my invention is:—

1. In a refrigerating device, in combination, a 20 refrigerator cabinet, a freezing unit insulated from the cabinet interior to produce an isolated freezing zone, a cooling unit distinct from said freezing unit and arranged in heat interchange contact with the air in said cabinet and capable 25 of being periodically defrosted without lowering the temperature of the freezing zone of said first mentioned unit below freezing temperature, said cooling unit including a float chamber, a refrigerant control valve controlled by a float in said 30 float chamber and having an outlet leading exterior to said float chamber and opened on the lowering of the float in said chamber, said freezing unit being in direct communication with said outlet and receiving refrigerant therefrom, said 35 freezing unit having its outlet connected to the said float chamber whereby the latter receives refrigerant therefrom, and a suction outlet from said float chamber.

2. In a refrigerating device, in combination, a 40 refrigerator cabinet, a freezing unit insulated from said refrigerator cabinet, a cooling unit exposed within said cabinet and including a float chamber, a valve float-controlled by the level of refrigerant in said float chamber, and means 45 whereby said valve directs the major flow of refrigerant direct to said freezing unit and a more restricted flow to said cooling unit on the opening of said float controlled valve.

3. In a refrigerating device, in combination, a 50 refrigerator cabinet, a freezing unit insulated from said refrigerator cabinet, a cooling unit exposed within said cabinet and including a float chamber, a valve float-controlled by the level of refrigerant in said float chamber, said valve having two outlets for the refrigerant on the opening of the float valve, one outlet being in direct communication with said freezing unit and the other outlet being in direct communication with said 55 cooling unit.

4. Means as claimed in claim 1 in which said freezing unit is provided with a casing thereabout and a motor-compressor unit for circulating the refrigerant is controlled by a thermostatic switch, the temperature influenced means of which has an extension in thermal contact with the said casing of said insulated freezing unit, whereby the thermostatic switch is subjected to an intermediate temperature between that of the freezing element and that of the 70 surrounding atmosphere in the cabinet.

5. In a refrigerating device in combination, a 75 cabinet, a condenser, a cabinet cooling unit having a float tank, freezing coils separate from said tank for producing a sharp freezing zone in said

5 cabinet, a valve casing mounted on said tank, a conduit leading from the condenser to said valve casing, a conduit leading directly from said valve casing exteriorly of said tank to said freezing coils, a suction conduit leading directly from said freezing coils to the interior of said float tank, a valve directing refrigerant clear of the said tank to the conduit leading to the freezing coils, and a float mechanism arranged within the float tank 10 controlling the operation of said valve, said float tank having a suction outlet.

6. In a refrigerating device, the combination with a cabinet, a horizontal control tank having cooling coils for cooling the interior of said cabinet, a condenser, and freezing coils separate from said tank for producing a sharp freezing zone in said cabinet, of a valve casing having an orifice connected with the condenser and an orifice connected with the freezing coils, a valve slidably mounted in said casing and controlling the flow of refrigerant, said valve permitting a main flow of the refrigerant directly into said freezing coils and a restricted flow directly into said control tank, means connecting the freezing coils with

said control tank whereby the vaporized and excess refrigerant from said freezing coils is received in said control tank, a pivotal arm mounted within the control tank adjacent to said valve orifice and operatively connected with said valve, 5 a suction outlet from said control tank, and a float connected to the free end of said pivotal arm.

7. In a refrigerating device, a cabinet, a refrigerant condensing unit, a refrigerant control valve, freezing coils enclosed within a chamber isolated from the cooling chamber atmosphere within the cabinet to produce a sharp freezing zone, means for conducting the refrigerant from said valve to said freezing coils, a refrigerator 10 cooling unit exposed to the atmosphere within said cabinet and connected with and receiving refrigerant from said isolated sharp freezing coils, means within said cooling unit for controlling said valve, and thermostatic means within 15 said cooling chamber and connected with the freezing chamber to control the operation of the condenser unit.
